UNITED STATES PATENT OFFICE.

CYRUS HAWKINS, OF CAMDEN, NEW JERSEY.

AUTOMATICALLY REGISTERING FEEDER.

Application filed September 18, 1925. Serial No. 57,155.

My invention relates to feeding and delivery of paper or card stock to an automatic die stamping press.

A purpose of my invention is to automatically feed to such exact registry that the same sheet or card may be fed through successively for printing in several colors in correct registry.

A further purpose is to secure perfect registry of successive sheets or cards with definite positions upon a turntable that are adapted successively to register with a die and counter die.

A further purpose is to provide a turntable with laterally extending fingers to support the major portion of the sheet or card and then to clamp the inner edge of the sheet or card to definite position down against the outer edge of the turntable, using a number of positions preferably corresponding to the number of operations to be performed.

A further purpose is to secure perfect registry between successive positions of a turntable and the counter die of a press to which it is attached by pin-locking it into registry during the printing operation the pin being tapered to preliminarily draw the turntable to position of exact registry.

A further purpose is to avoid the need for careful adjustment of a number of sets of stops or gages for the sheets or cards by having a single set of stops or gages and by adapting this single set to use at successive positions of the turntable.

A further purpose is to use stops which do not turn with the feeding mechanism for the stock instead of stops which turn with it.

A further purpose is to provide a turntable with a set of fixed stops or gages separate from the table for use during the period that the turntable is locked, which stops enter the table to position the stock, affording means for obtaining exact positioning of sheets or cards upon the table. These stops preferably come up from beneath and subsequently drop below the table, both during the period when the turntable is locked to definite position.

A further purpose is to have common support for the pin-lock and the stops or gages.

A further purpose is to automatically de-

liver the cards or sheets to the turntable 55 while the turntable is locked and with the gages in position, placing the sheets or cards initially in approximate position and then resiliently combing or pushing them to the 60 gages.

A further purpose is to push or comb the cards to final position by springs preferably carried upon and extending from a comber shaft.

A further purpose is to make the distance 65 between the combing mechanism and the table adjustable so as to adapt the combers to accommodate sheets of different sizes.

A further purpose is to comb or push the sheets or cards forwardly to contact 70 with the bottom gages and laterally to connect with a side gage.

A further purpose is to ensure perfect registry of the cards with their gages at the time that they are clamped to the table by 75 frictionally pulling them against the gages and clamping them to the table, clamping preferably while they are being frictionally pulled into the gages.

A further purpose is to mount frictional 80 devices upon the turntable which engage the forward part of the stock preferably just after completion of the pushing or combing operation and then pull the stock rearwardly into contact with the gages.

A further purpose is to resiliently clamp the stock—card or sheet—to position upon a turntable during the period in which it is being frictionally pulled against the gages and while the turn table is locked to position.

A further purpose is to release the lock-pin and remove the gages from the operative position after a new card or sheet has been clamped to the table and after the 95 printing stroke upon the card in printing position; and then to forwardly advance the turntable to bring another card or sheet to position under the counter die which at the same time brings the turntable to position 100 to receive another sheet or card.

A further purpose is to remove the printed stock from the turntable while the latter is locked in a new position.

A further purpose is to provide a turntable having a plurality of positions adapted to successively receive the cards or sheets with a single set of stops or gages for use

with the stock in each position, successively, for definitely positioning the successive cards.

A further purpose is to provide the stops or gages with an adjustment to adapt them to setting to perfect registry with the die and counter die.

A further purpose is to adapt a feeding turntable to bodily adjustment toward and from the die and counter die in order that it may be adapted to use with variant sizes of sheets and cards. I do this by mounting the turntable upon a support movable toward and from the press.

A further purpose is to swing the guides for the turntable support by an apron hinged to the press at one side and removably locked to the press at the other side.

A further purpose is to pivotally mount the driving mechanism for the shaft by which the turntable is rotated upon the shaft and to drive it from the side, providing connections between the parts so that adjustment of the driving mechanism is permitted laterally and longitudinally with respect to the shaft.

A further purpose is to provide for the shaft by which the turntable is rotated, driving mechanism slidable along it and rotatable with respect to it, mounting this mechanism upon the shaft and driving it from the side through a flexible shaft containing a universal joint.

A further purpose is to drive the operating gear of the feeder continuously in order to provide continuous motion for devices operating various features of the mechanism.

A further purpose is to use a Geneva drive for the table and to use the driving shaft of the table as a cam shaft to control the opening and closing operations of the frictional pullers.

A further purpose is to latch the frictional pulling mechanism by the movement of the locking and gaging devices and to release the latch by means timed with the table-turning mechanism.

A further purpose is to carry successive sheets or cards from a pile and deposit them upon the turn table while the turn table is at positions of rest.

A further purpose is, during each period of rest to simultaneously utilize successive positions of the turntable, at the first position, feeding the stock to it, adjusting the sheet and clamping it; in the second position, applying a detector adapted to avoid stamping during the succeeding stroke if the card or sheet has not been properly placed; in the third position, to perform the printing operation; and in the fourth position to remove the printed card for deposit on a suitable tray.

A further purpose is to provide an automatic trip mechanism, associated with the

turntable and cooperating with the sheet or card thereon, if present, for tripping the press and preventing the impression from taking place whenever a sheet or card is not fed.

A further purpose is to continue to operate the turntable notwithstanding the tripping of the press and to provide for resumption of the normal operation of the press as soon as and whenever a card or sheet is present in printing position.

Further purposes will appear in the specification and in the claims.

I have preferred to illustrate my invention by one form only of the many in which it can be embodied, selecting a form which is practical, efficient and thoroughly reliable and which at the same time well illustrates the principles of my invention.

Figure 1 is a section of a portion of a press showing in top plan view my automatic feeding device applied to it.

Figure 2 is a front elevation of the automatic feeding mechanism attached to the press but with parts of the press omitted.

Figure 3 is an enlarged front elevation corresponding generally with Figure 2 but showing the upper section only.

Figure 4 is a fragmentary side elevation showing a portion of the press and the upper part of my feeding mechanism.

Figure 5 is a fragmentary side elevation corresponding generally with Figure 4 but showing a lower portion of the press and the lower part of my feeding mechanism.

Figure 6 is a section of Figure 5 taken upon line 6—6 and showing my structure largely in front elevation.

Figure 7 is a fragmentary top plan view to enlarged scale of structure seen in Figure 1, with additional structure, a portion of the press being broken away.

Figure 8 is a top plan view of the structure seen in Figure 7 but with parts removed to show structure beneath them.

Figure 9 is a top plan view corresponding somewhat with Figures 7 and 8 but broken away in part to show the universal joint and Geneva movement.

Figure 10 is a fragmentary top plan view corresponding with Figure 9 to show clamp operating mechanism and the Geneva movement.

Figures 11 and 12 are fragmentary horizontal sections, from which parts have been broken away, of the front portion of the mechanism, i. e., that portion farthest from the press.

Figure 13 is a fragmentary side sectional elevation, with parts broken away, of the card carrier mechanism in position to pick up the card.

Figure 14 shows the card carrier mechanism in delivering position to place the card, the view corresponding to that of Figure 13.

Figure 15 is a perspective view of the apron by which my mechanism is mounted on the press.

Figure 16 is a fragmentary section and side elevation of part of the feed for lifting the paper pile.

Figure 17 is a section and fragmentary elevation of the combing shaft cam and connections.

10 Figure 18 is a fragmentary side elevation, partly broken away, showing the lock-operating cam, locking pin, gages and connecting mechanism.

15 Figure 19 is a fragmentary top plan view showing card aligning and locking mechanism.

Figures 20 and 21 are sections taken upon line 21—21 in Figure 19, but showing the parts in different positions.

20 Figure 22 is a fragmentary section taken upon line 22—22 of Figure 19.

Figure 23 is a fragmentary section of Figure 19 upon line 23—23.

25 Figure 24 is a section of Figure 19 taken upon line 24—24.

Figure 25 is a fragmentary top plan view of the table in Figure 19 with parts removed.

30 Figures 26—34 relate to the mechanism for delivering the sheets or cards from the turntable. For the sake of greater clearness this mechanism has been wholly omitted in the earlier figures.

35 Figure 26 is a fragmentary side elevation of the card delivery and pickup mechanism.

Figure 27 is a plan of the mechanism, the delivery gripper being shown in an outer position latched open and directed toward the card, preparatory to moving in and seizing the card.

40 Figure 28 shows a portion of the delivery mechanism shown in Figure 27, but in a more advanced position in which the delivery gripper has swung in and seized the sheet or card.

Figure 29 is an enlarged fragment of Figure 27.

Figure 30 is a right hand end elevation of Figure 29.

45 Figures 31, 32 and 33 are views corresponding to Figure 30 but with the jaws in different positions.

Figure 34 is a left hand end view of Figure 33.

50 Figures 35 and 36 are side elevation diagrammatic views illustrating the detector and tripping mechanism in operating position. In Figure 35 a sheet or card has been absent and the detector is shown preventing the next impression while in Figure 36 a card has been present and the next impression is taking place.

In the drawings similar numerals indicate like parts.

55 While I have applied my invention to a

press, and a press of the general character known as an embossing or die stamping press, I recognize that the invention is broader than this would represent and can be applied where paper or card stock is to be handled in connection with other types of press and with other mechanism which would not properly come within the press class, depending only upon the requirements of the operations performed, justifying feeding mechanism of the character shown.

Describing the press as well as the feeding mechanism in explanation therefore, and not in limitation, I show as follows:

I aim to make my feeding mechanism universal in its application in that it shall be capable of being applied as an attachment to existing presses or other machines as well as of being built into the press or otherwise applied to it when the press is new. In either case it is desirable that the mechanism be movable into and out of operative position at will. I have illustrated it as an attachment to an old press.

When applied as an attachment, my entire feeding structure is hinged to one side of the front of the press and when not in use may be swung to one side—out of the way to permit adjustment of the make ready or other structure at the front of the press.

The combined machine divides itself naturally into the press, connecting members, the relatively fixed supporting and guiding apron structure, sliding frame adjustable to different sizes of stock, and operating mechanism.

The press.

The press may be of any suitable type. I show merely fragmentary portions. It is best seen in Figures 1 to 9, and in Figures 35 and 36, the structure in Figures 35 and 36 being a diagrammatic representation of one way in which my detector mechanism may be used to prevent an impression whenever a card or sheet is absent. The press is driven by a main gear 51 whose main shaft 52 is provided with an eccentric 53 at each end. These operate compression rods 54 that co-operate to raise and lower the press plunger 55. The counterdie 56, die 57, chuck or die holder 58, press platen 59 all old, are best seen in Figures 1 to 4.

Connecting members between the press and feed structure.

These are well shown in Figures 2, 7 and 9. They comprise hinges upon one side of a supporting apron 60 and fastening mechanism upon the other. The hinges are formed by brackets 61 mounted upon one side of the front of the press, cooperating with brackets 62 upon the side of the apron

and hinge pintles 63. The apron forms a hinged support for the whole structure.

The fastening or locking mechanism upon the other side of the press normally maintains the apron in operating position. This fastening mechanism is shown as comprising a bracket 64 bolted to one side of the press, a cooperating bracket or lug 65 upon the apron and a screw stud 66 for fastening the 10 apron securely to the press.

Main supporting structure of the feeding mechanism.

This is best seen in Figures 2, 5, 6, 12 and 15 16 and includes the apron 60 seen in detailed perspective in Figure 16 and a base or bracket 67 forming a track and guideway for the slidable frame divided from it along any suitable lines for convenience in construction.

The base is securely fastened to the apron by means of bolts 68 and 69 through the inner vertical plate portion 70 of the bracket into raised faces 71 and 72 upon the apron, 25 and the apron and bracket are thus a rigid unit.

The bracket provides a track or guideway along which the slidable frame 73 is adjustably positioned.

30 Runways 74 are formed upon the upper side of the bracket 67, and receive the sliding base 75 of the frame 73, gibs 76 being secured to the bracket, adjacent each runway, to engage above the edges of the sliding base. The sliding base has secured thereto, 35 on the lower side thereof, an internally screw-threaded boss 75^a, in the nature of a nut, which receives a long screw 75^b mounted in suitable bearings of the bracket 67 and 40 formed, at its outer end, with a squared portion 75^c for receiving an operating handle or the like. By turning the screw 75^b in one direction or the other, the sliding base 75, and consequently the frame 73, can be 45 moved to any desired extent towards or away from the press.

Slidable frame.

This is best seen in Figures 1, 5, 6, 9 and 50 12. It is adjustably positioned along the base as already described and forms bearing and guideway support for the operating mechanism of the feed apparatus.

Functionally the different mechanisms 55 carried by the slidable frame are designed to severally place, handle and remove sheets or cards for the turntable 79 in order to adapt the turntable to feed the successive sheets or cards to the press in positions of 60 exact registry.

These functions include bringing the sheets automatically from an elevator pile to the table, exactly positioning and clamping the successive sheets automatically to 65 position upon the table, placing and main-

taining the table in exact registry with the die and counterdie of the press during the printing operations, interspersing periods of rest between the operations, providing means to stop an impression whenever there is no 70 card or sheet present to receive it and removing the printed sheets or cards from the table as fast as they are printed.

The slidable frame 73 comprises a side portion 80, Figures 5 and 6, a front portion 81 75 and the sliding base 75. In transverse section the slidable frame is an L except at the front 81 which forms a vertical guideway support for the supply elevator.

I show these side, front and bottom portions of the slidable frame as comprising a single casing. Obviously they may be made up of several pieces and in many cases this will be probably more easy than making the frame an integral member.

Power drive.

All the different mechanisms of the slidable frame are driven from a vertical shaft 83, Figures 4, 5 and 6, that is supported in 90 the upper and lower bearings 84 and 85.

These bearings are carried upon brackets 86 and 87 bolted to the side portion of the frame. The weight of the shaft is supported on a thrust-bearing 88 above the lower 95 bracket 87.

I drive the vertical shaft from the gear 89 which meshes with the main gear 51 of the press.

The gear 89 is mounted upon a shaft 77 100 supported in the bearing 78 carried upon the apron. The inner end of this shaft makes universal joint connection at 91 with a splined shaft 92 adapted to drive the vertical shaft 83. The splined shaft carries a 105 worm 93 mounted to drive a worm wheel 94 (Figure 9) upon the vertical shaft, the shroud or housing 95 of the worm, which rests upon the thrust bearing 88, being pivotally carried by the vertical shaft.

The arrangement is one in which the splined shaft and housing will angularly accommodate themselves to driving connection in the different positions to which the slidable frame may be adjusted along the runways 74 by means of the screw 75^b. The worm is mounted to slide on the splined shaft.

I mount a bevel gear 97, Figure 4, on the vertical shaft somewhat above the housing 95 120 to drive a main cam shaft 98 that in turn drives a number of different mechanisms.

The gearing from the gear 97 to the cam shaft 98 includes bevel gear 99 counter shaft 100 and bevel gears 101 and 102, Figures 125 4 and 6.

The counter shaft 100 is carried in bearings 103 and 104 upon bracket 105 which is bolted to the side of the slidable frame, as best seen in Figure 4. Somewhat above the 129

bevel gear 97 I provide on vertical shaft 83 a cam 106. This cam provides rocking angular motion to the shaft 107 of the clamping cam 108.

5 The upper bearing 84 of the vertical shaft, carried by the bracket 86, is placed above the cam 106. Above the upper bearing 84 I place a Geneva driving disc 109 best seen in Figure 10 for driving the turntable 79.

10 This Geneva disc cooperates with a suitable Geneva stop cam 110 and is of a usual four way Geneva type.

15 Concave portions 111 and slots 112 of the Geneva stop cam cooperate with the circular periphery 113 of the disc 109, the pin roller 114 carried by an extension 114^a of such disc and the relieved portion 115 of such disc, so as to give successive periods of rest and turning to the Geneva stop cam by the continuous motion of the disc. The Geneva disc is shown fastened to the vertical shaft by means of a suitable stud 116.

20 Above the Geneva disc I rigidly mount a spur gear 117, (Figure 8), upon the vertical shaft and use this spur to drive another gear 118 loosely mounted upon the upper end of the hollow shaft 119 of the turntable.

Main cam shaft.

25 The so-called main cam shaft 98 (Figure 6) driven from the vertical shaft 83 by the counter shaft 100 carries most of the operating cams of the automatic feed and is best seen in Figures 1 to 4, 6, 11 to 14, 17 to 19, 26, 27, 35 and 36. It is shown mounted in bearings 120, 121 and 122 carried by the frame. Most of the cams upon this shaft show best in Figure 6 which does not however show the double cam operating the card delivery mechanism (best seen in Figures 26 and 27) nor the cam operating the detector mechanism (shown in Figures 35 and 36).

30 Beginning from the right hand side of Figure 6, a crank 123 moves the suction cup carrier 124 (Figures 4, 13 and 14) back and forth to deliver successive sheets of paper from the elevator pile 125 to the turntable 79.

35 The cam 126 (Figures 6 and 17) mounted next to the crank 123 is used to control the height of the elevator pile 125, (Figure 4), that is, to maintain the top of the pile at a level proper for picking up the top sheet by the suction cup carrier.

40 The cam 127 operates the locking and stop mechanism of the table. As soon as the table comes to rest in each new position this cam operates mechanism whereby the table is pin-locked to exact position and whereby stops or gages 128, 129 and 130 (Figures 4 and 7) for the paper rise for use in exact positioning of the next sheet of paper fed to the table.

45 The cam 131 operates the combing mechanism whereby each sheet or card after it has

been placed to approximate position upon the table is combed or pushed to contact with the stops, 128, 129 and 130.

50 The cam 132 cooperating with the roller 133 on bell crank lever 134 (Figure 4) is the dipping cam which functions to cause the suction cup 135 to dip down when it has moved back over the supply pile 125 to pick up a new sheet or card.

55 Cams 136 and 137 (Figures 26 and 27 and not shown in the other figures) together form one rigid and permissibly integral member. They operate the pick up or delivery (discharge) mechanism whereby each card or sheet after it has been printed is 80 picked up and removed from the turntable and is delivered face up upon any suitable adjoining table or receptacle.

Paper elevator mechanism.

60 This is best seen in Figures 1, 2, 4, 5, 11, 13, 14 and 16, and may be of any suitable type. As illustrated it comprises a horizontal supporting bed 138 (Figure 5) mounted to slide vertically in guideways 139 (Figure 90 11) in the front portion 81 of the slidable frame. Gibs 140 maintain the bed within its guides or runways.

65 The bed is gradually fed upward to maintain the level of the pile by means of a vertical screw 141. This screw is mounted in bearings 142 and 143, Figure 2, that are carried by the frame and it is operated from the cam 126 on the main cam shaft by means of elevator lifter link 144, arm 145, pawl 146 and ratchet 147 (Figures 2, 11 and 17) turning shaft 148 (see Figure 17). The shaft 148 carries a gear 149 meshing with corresponding gear 150 upon the screw.

70 The bed of the elevator supports underneath a rod 151 (Figure 5) which carries at its inner end a half-nut 152 normally meshing with the thread 153 of the screw 141. As best seen in Figure 5, this rod is spring pressed to hold the half-nut into mesh with the thread of the screw being carried in bearings 154 and 155.

75 The rod 151 is provided with a head 156 by which it may be pulled outwardly against the spring 157, pulling the half-nut 152 away from meshing with the vertical screw. When this is done the bed is free to be moved up and down along its runways. This adapts it to easy positioning by hand at any time.

80 Figure 16 shows diagrammatically means for stopping the feed by lifting the pawl 146 from engagement with the teeth of the ratchet 147 whenever the pile is sufficiently high.

85 The float member 308 is mounted upon one end of a lever 309 and engages the top sheets of the pile near one edge.

90 The lever 309 pivoted at 310 has its other end connected by link 311 and lever 313 130

and link 314 with the pawl 146 and when the float is sufficiently high it operates through lever 30, lever 313 and link 314 to lift the pawl from the ratchet.

5 When the pile gets low the float sinks and permits the pawl to reengage the ratchet making the feed again operate.

The turntable.

10 In the illustration the turntable 79 (Figures 1 to 4, 7 to 11, and 19 to 27) rotates with intermittent periods of rest and motion, one-quarter as many times as the revolutions of the press.

15 The top of the turntable, preferably a plate, is fastened rigidly to the top of the Geneva stop cam 110, carried by a hollow shaft 119 having its bearings in a boss 86^a extending from the upper bearing 86 of the shaft 83. Frictional pulling members 158 (Figure 7) are also mounted one on each of the four sides of the top of the table.

20 After the table comes to rest it is brought to a final, accurately located, position and locked therein. This is effected by means of a tapered pin 159 (Figs. 18 and 20-22) carried by an intermittently elevated platform 213, which pin enters in one of four sockets 161 adjustably secured upon the turntable 79. The sockets 161 are formed with holes 160 having a corresponding taper to that of the pin 159; so that as the pin enters the socket the table will, if necessary, be given the slight movement necessary to bring it 25 to a final accurate position. The sockets come, one after the other, into operative relation with the pin and are given an initial adjustment such that each succeeding portion of the table comes into precisely the same position with respect to the dies.

30 The platform 213 is secured to the upper end of a stem 406 (Fig. 18) which slides through a sleeve 407 carried by the bracket 105. A compression spring 409 is disposed 35 between the platform 213 and bracket 105 and tends to hold the platform in a raised position which is limited by the engagement of a pin 410 in a slot of the sleeve 407. The stem 406 is provided at its lower end with a 40 horizontally extending foot 411, the top of which is engaged by a roll 412 mounted on the end of a cam lever 413. A roll 414 on the other end of such lever engages the cam 127 on the cam shaft 98.

45 When the turntable is in motion, the high part of the cam 127 is engaged by the roll 414 so that the platform 213 is held in a lowered position where the pin 159 is out of the path of the turntable. After the turntable comes to rest, the low part of the cam 127 comes opposite to the roll 414, whereby the platform 213 is permitted to be raised by the action of the spring 409, so that the pin 159 enters the tapered socket immediately 50 above it and effects a fine positioning of

the turntable and a locking of the latter. Before the turntable starts to move again, the high part of the cam 127 will have come into engagement with the roll 414, and the platform 213 will be lowered out of the way 55 of the turntable.

60 The top of the platform 213 is formed with two pairs of slots 415 which correspond in position with two pairs of slots 162 formed in each edge of the turntable (Figures 8 and 11). Adjustably mounted in one pair of these slots 415 are a pair of end gages 128, 129. If the sheet or card to be fed is wide, these gages 128, 129 will be placed in the slots 415 which align with the outer pair 65 of table slots 162; if it is narrow, the gages will be placed in the slots 415 which align with the inner pair of table slots 162. By moving the gages in the slots, a fine adjustment of the ultimate position of the sheets 70 with respect to the dies may be obtained.

75 In the top of the platform 213, and extending transversely thereof, parallel with the edge of the turntable, are formed two slots 416, 417, one at the left and one at the right hand end. In one of these slots is mounted the slide 130^a of a side gage 130, this gage being adjustable in such slot in the same way as the end gages 128, 129 are adjustable in their slots 415. Normally, and 80 especially where the frictional pullers described below are used, the side gage 130 will be placed in the left-hand slot 416. However, where right-hand registering is for any purpose desired, it will be placed in 85 the right-hand slot 417.

90 After the table has been pin-locked to exact position the suction cup carrier 124 drops a sheet or card upon the table, and the end combing members 163, 164 and side 95 combing members 165, 165^a (Figures 1, 3 and 7) are operated by cam 131. The combing members preferably comprise light spiral springs and turn upwardly to push the paper 100 against the stops.

105 There are two of these so-called end combers, which operate together, and two of the so-called side combers, either of which latter may operate, but not usually both. The combing members push the paper simultaneously in two directions to and against the end and side gages.

110 One of the frictional pullers 158 (Figures 7, 20 and 21) has meanwhile moved forward 115 with open jaws and frictionally clamps the sheet or card. It now moves back, the sheet or card being lightly held between rubber bearing members 166 and 167 of the jaws of the pullers:

120 During the period in which the puller moves rearward, by pulling the sheet or card against the stops, a gripping clamp 168 (Figures 1 and 9) is released and securely 125 clamps the sheet or card to the top of the turntable.

When the sheet is clamped by the clamp 168, its front edge is supported upon the edge of the turntable 79, and its side edges are supported by fingers 400, a pair of which 5 extend from each side of the turntable and are adjustable along the edge of the turntable so as to be available for supporting the edges of sheets or cards of varying widths. Each of these fingers 400 is carried by a 10 dovetail slide 401 mounted in a correspondingly shaped groove formed in the under side of the table, parallel with and adjacent the edge of the latter. By moving the slides 401, the fingers 400 may be adjusted so as to 15 support the edges of any sheet or card in spite of variations in the width of the latter.

It is desirable for the impression of the press to take place immediately after the table has been pin locked to definite position. This affords ample time for the operation of an automatic detector in position 20 of the table after the impression has been made.

The automatic detector applied in the second 25 position of the table should operate after the impression but during the same period of rest as that of the impression in order that the operation of the detector will apply to the sheet after it reaches printing position.

After the operation of the detector the pin-lock and gages move down out of the way; the Geneva mechanism then moves the table forward another one-quarter turn to 35 advance the cycle, and an impression is then made or not according to the finding of the detector in its last operation.

The combers.

40 After the sheet or card has been fed, by the suction cup carrier mechanism to be described below, towards the end gages 128, 129, it is moved into closer registry with such end gages, and the side gage 130, by 45 the end combers and a side comber.

Two rails 402 extend forward from the front member 81 of the slideable frame 73 (Figures 1, 6 and 11). Upon these rails, so as to be adjustable towards and from the turntable, according to the length of the sheet or card, is mounted a frame 403 formed at its ends with bearings for an end comber shaft 176. To this shaft are secured, by means of collars 184, the end combers 163, 55 164, the combers, as has been said, preferably consisting of light spiral springs.

Upon the end of the shaft 176 is mounted a pinion 175 (Figure 4) with which meshes a quadrant gear 174 pivoted upon the frame 60 403. An arm 173 extends rearwardly from the quadrant gear 174 and has pin and slot connection with a link 169 (Figures 4 and 17) which extends downwardly at one side of the machine and is provided, at its lower 65 end 170, with a cam roll 171 which bears

upon the cam 131 carried by the cam shaft 98. When the cam 131 depresses the link 169, the shaft 176 is rocked in a clockwise direction, thereby to cause the end combers 163, 164 to engage against the rear of the sheet or card and press the latter towards the end gages 128, 129. When the low part of the cam 131 comes opposite to the roller 171 the end combers are rocked backward and downward by the action of a spring 177 connected between the quadrant gear 174 and a pin 179 on the frame 403.

Mounted in transverse guideways 404 formed in the frame 403 are a pair of stands 405 carrying side comber shafts 182 upon 59 which are mounted side combers 165, 165^a. These side comber shafts carry beveled pinions 181 which mesh with corresponding pinions 180 on the end comber shaft 176; so that the rocking movements of the end 65 comber shaft are imparted to the side comber shafts, the side combers operating in the same way as the end combers. The stands 405 are adjustable lengthwise with respect to the frame 403, so as to be available for 90 use with sheets or cards of different widths. Normally only one of the side combers will be used at a time, either 165 or 165^a. Which of the side combers is employed will usually depend upon the side at which the side gage 95 130 is placed. The side comber will be put in use at the opposite side of the sheet or card to that at which the side gage 130 is located.

Card gripping mechanism. Figures 1-4, 6, 100 7, 10, 11, 14, 15.

This comprises four clamps 168 (Figure 1) one mounted upon each of the four sides of the turntable, spring-pressed to clamping 105 position, and a single clamp cam 108 adapted to raise each clamp against the action of its spring 184 preferably at the time the sheet or card last printed is taken hold of by the card delivery mechanism. 110

The cam 108 will maintain the clamp 168 in raised position from then on during a portion of the succeeding period of rest until the incoming sheet or card has been exactly positioned against the stop gages and during the time in which the frictional pullers are maintaining the sheet or card exactly to position it will release and drop to tightly clamp the sheet or card to the table. 115

There are four clamps 168 each comprising a T-shaped lever pivotally mounted upon a bearing member 185 and spring-pressed toward closure by means of a spring 184 upon pins 186 of the bearing 185. 120

The inner end 187 of each clamping member is slightly beveled to afford more easy sliding engagement with the corresponding bevel 188 (Figure 10) upon the rear side of the clamping cam 108. 125

The clamping cam 108 is fastened, by 130

means of a stud 108^a to a shaft 107 which passes down axially of the turntable, through the hollow shaft 119, and at its lower end rigidly carries with it a crank arm 189.

5 The outer end of this arm carries a roller 190 which engages the cam 106 mounted upon the vertical shaft 83.

10 The spiral spring 191 (Figure 4) mounted upon the bearing 192 of the turntable resiliently presses the arm 189 so as to maintain the roller 190 in continual engagement with the cam 106.

15 The cam 106 mounted upon the main vertical shaft of the slidable frame is best seen in Figure 10.

In the position of the parts shown in Fig. 10, the Geneva stop cam 110 has nearly completed one of its quarter revolutions. By the time it has finished such quarter revolution, the center lines of the table will come into the position indicated by the dotted lines, as distinguished from the chain lines, of the figure, and the gripper 168 at position α (which gripper secures a stamped card or sheet in place on the turntable) will have reached a location in which its beveled end 187 is closely adjacent the beveled edge 188 of the gripper actuating cam 108. The Geneva stop cam, and the turntable, will then stop, but the Geneva disk 109 and cam 103 will, of course, continue to rotate. Immediately after the stoppage of the turntable, the first step 193 of the cam 106 will engage the roll 190, and thereby cause the gripper-actuating cam 108 to be moved in a clockwise direction, into the position shown in Fig. 7. This movement of the cam will cause the gripper 168 then near position α to be lifted, thereby to release the stamped card or sheet. The movement of the gripper-actuating cam 108 will not, however, be sufficient to carry it way from above the gripper 168 then near position y , which latter gripper was opened during the preceding cycle and maintained open by its engagement beneath the cam 108. Thus the gripper 168 near position y is held open ready to receive a new sheet. Because of the circular portion 195 of the cam 106, the gripper-actuating cam 108 remains stationary during a large part of the period during which the turntable is at rest, whereby the gripper 168 near position y is maintained open during this part of the period, and time is given for the feeding and registration of the new sheet.

Shortly before the turntable is about to start its next quarter revolution, the second step 197 of the cam 106 engages the roll 190 and thereby causes a slight further movement of the gripper-actuating cam 108 in a clockwise direction. This moves the cam 108 from the position shown in Fig. 7, in which it holds open the gripper 168 near position y , into a position in which such gripper 168 is freed and allowed to close under the ac-

tion of its spring 184, whereby the newly fed sheet is clamped in position.

After the turntable has started its movement, the roll 190 follows a depression of the cam 106, the gripper-actuating cam 108 being thereby caused to move in a contra-clockwise direction back to the position shown in Fig. 10. This movement of the cam has no effect upon the grippers 168, for the gripper just closed has moved away from the cam 108 and the gripper just opened travels beneath the cam 108 and is maintained open thereby.

Frictional pullers and operating mechanism.

90

Four frictional pullers are provided, one for each of the grippers 168. These pullers are best seen in Figures 7, 8, 19 to 25.

The guideways 198 extend only partially through the top of the turntable except at the rear where the head 200 of each slide extends through the table and carries a pin 201, that projects top and bottom to engage operating mechanism.

The diagonal slots 198 (Figure 19) are guideways in the turntable for the pullers, the pullers advancing and receding in these slot guideways upon slides 199. A hinge bracket 202 supports the upper jaw member 203 of the puller.

This jaw is spring-pressed toward closure by means of a spring 204 fastened to the slide at 205 and passing through a perforation 206 in the upper jaw member.

The contact faces 166 and 167 upon the upper and lower jaw members are conveniently rubber discs and provide the frictional holding surfaces.

The slide is adapted to automatic advancement and retraction and opening and closing.

The means for advancing the slide comprises a lever 207 one for each of the four slides, pivoted upon the top of the turntable by means of a screw stud 208. The inner end of each of these levers is provided with an upwardly extending pin 209 which engages a stud 210 mounted upon the hub of the clamping cam.

As the turntable rotates these pins successively engage this stud and are pushed rearward to turn the lever and forwardly advance the slide, the outer ends of these levers making slot connection with the pins 201 so that angular motion of the levers result in sliding motion of the slides.

The stud 210 is set in such relation to the pins that the particular slide engaging the stud is fully advanced when it passes the stud.

When the slide has been forwardly advanced, it is opened (Figs. 19-21) by means of a lifting member 211 having a pin 212 which engages beneath the upper jaw 203 of the puller. One of these lifting members is provided for each puller and consists of a

120

125

130

square rod sliding freely through a suitable perforation in the turntable. As each puller comes around to the feeding position, its lifting member is adapted to be engaged by the top of a lever 214 (Figs. 8 and 19) which is pivoted, at 215, in a recess 216 of the vertically moving platform 213. The lever 214 is in general of L-form, and is normally pressed, by a spring 217, against a stop pin 218 in the bottom of the recess 216. The lever 214 is formed with an inwardly extending arm 219 carrying, at its inner end, a pin 220 adapted to engage a cam 221 secured to the spur gear 118. The spur gear 118, as has been described above, is loose upon the shaft of the turntable and meshes with the pinion 117 carried by the shaft 83. Consequently the cam 221 makes one rotation for each cycle of the press and performs its operation in connection with each successive puller as it comes to the sheet feeding position.

Mounted upon the underneath side of the turntable, pivotally supported upon the pins 223 and having slot and pin pivot connection at 201 with respective slides, I provide a lever 224 for each slide, with an arm 225 extending inward to engage a pin 222 upon the spur 118.

The cam 221 and pin 222 on the spur gear 118 are so placed that when the paper or sheet has been combed to position by the combers the cam 221 engages the pin 220 on the lever 219 moving this lever inward upon its pivot 215 and away from beneath the lifting member 211 of the upper jaw 203 of the frictional puller. This jaw now springs shut effecting frictional gripping of the sheet or card.

The pin 222 upon the spur 118 now engages the toe 226 of the lever 224 underneath the table and slowly turns this lever to retract the slide and it is during this retraction of the slide while the card is slipping between the closed jaws of the puller that the gripping clamp is released to firmly clamp the papers to position upon the table.

Card delivery mechanism. (Figures 26 to 34.)

The card delivery is the fourth operation.

The pick up and delivery mechanism is mounted upon a bracket 227 bolted to the front plate 81 of the slidable frame and operated and partly supported by an extended portion 228 of the main cam shaft.

The whole mechanism slides along its guideway mount 229 and along the extension 228 of the main cam shaft in order to adapt it to operation upon different sizes of sheets and cards.

The carriage 230 of this structure carries a threaded nut 231 upon an adjusting screw 232 which positions the carriage and the whole pick-up structure with respect to its distance from the turntable in order to per-

mit adjustment to the edge of different sizes of sheets or cards.

The carriage is slidable along the guideway 229 and extends upward to form hinge bearings 233 and 234 that pivotally support an extended arm member 235. The upper portion of the carriage also provides a pivotal anchor 236 for a connecting link 237 that operates the trigger 238 to close the delivery gripper 239 upon the card. The arm frame member 235 is pivoted upon vertical shaft 240, which is adapted to oscillate in the bearings 233 and 234.

This shaft 240 is rocked back and forth by means of a cam 136 upon the outer end of the cam shaft extension 228 in cooperation with a roller 241 upon arm 242 fixed to its lower end.

The roller 241 is maintained to its duty against the cam by means of a spiral spring 243 surrounding the lower end of the vertical shaft 240 and having one end 244 fastened to the carriage 230 and the other end 245 fastened to the arm 242.

The upper end of the shaft 240 is provided with a segmental beveled gear 246 which meshes with a beveled gear 247 upon a horizontal shaft 248 that is supported within bearings 249 and 250 upon the upper side of the arm member 235.

The delivery gripper 239 is mounted upon the end of the horizontal shaft 248; and the cam 136, by engaging the roller 241 upon the arm 242 of the vertical shaft 240, oscillates the vertical shaft and thereby oscillates the horizontal shaft 248 and the delivery gripper 239 so as to alternately direct this gripper inwardly to take hold of a sheet or card and outwardly to deliver it.

The arm member 235 is horizontally rocked upon the vertical shaft 240 as a pivot by means of a cam groove 251 in a cam member 137, the roller 252 which engages such groove being carried by a stud bolt 253 upon a bracket 254 extending from the lower portion of the arm member 235.

The delivery gripper 239 comprises an upper jaw 255 rigidly fastened to the horizontal shaft 248 and a lower jaw 256 loosely mounted upon the horizontal shaft.

The lower jaw 256 is spring pressed toward closure by means of a spiral spring 257 stretched between an anchor 258 upon an extended portion 259 of the upper jaw and an extended portion 260 on the lower jaw.

Pivotaly mounted upon the upper jaw 255 is a latch member 261, which cooperates with a lug 262 integral with the movable lower jaw 256, the lug providing a bearing surface for the latch member 261.

This latch member carries rigidly with it a laterally extending pin 263 bored to pass a trip rod 264.

The trip rod 264, pin 263 and latch member 261 are rigid with respect to one another.

pivoting as a unit at 263 on the jaw 255, the pin 263 having bearing in the jaw. A collar 265 is provided to maintain the pin 263 in place.

5 One end 266 of the trip rod 264 engages an opening member 267 which operates the latch to force open the gripper and the latch is held in open position by the tension of the spring 257 which presses the flat surface of 10 the lug 262 of the movable lower jaw against the flat end of the latch member 261.

This opening member 267 comprises a bent rod rigidly fastened to the housing portion 268 of the frame member 235.

15 Upon the other side of the housing 268 I pivotally mount the trigger lever 238. The position of this lever is controlled by the link 237 and the angular position of the arm member 235.

20 The position of the trigger lever is such that its toe 269 engages the end 270 of the rod 264, when the arm 235 has swung inward for another sheet or card and this engagement releases the latch causing the jaws 25 to spring shut upon the next sheet.

After a sheet has been seized by the jaws the arm 235 swings outward responsively to the cam 137 acting upon the roller 252 carried by the arm member and the horizontal shaft 248 then turns over by the action of the cam 136, swinging the gripper downwardly, under and outwardly to present the sheet or card in an outward direction. During the latter part of this swinging movement of the gripper, the opening member 267 engages the end 266 of the rod 264 to force open the jaws and release the card dropping it upon a suitable tray or other receptacle not shown.

40 The jaws, which are now open, turn back and, while open and extended toward the next sheet, the arm 235 moves inward to enable the jaws to seize the next sheet. When the jaws are sufficiently far inward, the trigger lever 238 engages the end 270 of the rod 264 tripping the lower jaw 256 so as to close upon the next sheet.

Figure 30 shows the jaws latched open and ready to move inward to seize the card while 50 in Figure 31 the jaws have moved inward, latched open, have been released, the card seized and are shown as beginning to turn over for card delivery.

In Figure 32 the jaws are in position at 55 which they are to be forced open by the latch to release the card and in Figure 33 the jaws have turned somewhat further and the card is released.

60 *The suction cup carrier mechanism. (Figures 1 to 4, and 12 to 14.)*

The suction cups function to pick up successive sheets or cards from the pile elevator at 272 (Figure 4) and to deliver them to the 65 turntable 79.

The carrier 124 is mounted upon a carriage 273 which is provided with a suitable guideway 274 within which it moves back and forth responsively to the operation of a crank arm 123 upon the outer end of the 70 cam shaft 98.

This crank arm 123 carries a rack 275 which engages a spur 276 upon a shaft 277 (Figure 1) within bearings 278 upon the housing member 279. 75

The shaft 277 does not itself move bodily. The gear 280 carried by this shaft meshes with a rack 281 on the carriage 273 of the suction cup carrier mechanism.

The rack 275 is held to its duty against 80 its spur gear 276 by an idle roller 282 carried upon a link 283 fastened to the housing 279.

By rotation of the crank arm 123 on the end of the cam shaft, the carriage is moved 85 back and forth along its guideway 274.

It is desirable to have a dwell at the rear end of the travel of the carrier 124 to afford time for the picking up of the sheet or card from the pile elevator. 90

This is provided for by mounting the carrier 124 beneath the carriage slidably upon rods 285 (Figure 13) and having the carrier spring-pressed rearward. Springs 284 press the carrier to the rear and when the 95 carriage moves rearward stops 286 (Figure 14) fastened to the housing 279 engages bolt projections 287, one on each side of the carrier.

The carriage 273 continues to move somewhat further to the rear against the spring action but the carrier 124 does not move any further, a period of dwell being obtained for the carrier in which the springs 284 are compressed, the rods 285 supporting the carrier 100 sliding through the carrier and compressing the springs. 105

During the period of dwell the suction cups 135 move down and pick up a sheet 110 from the pile.

The suction cups are carried at the lower end of a plunger 288 which in turn is carried upon a pin 289 supported within spaced forks 290 (Figure 4) of a rocking lever 291 mounted on a pin 292 in the lower portion 115 of the carrier.

The rocking lever 291 has a rearwardly extending portion 293 which is provided with a pin 294.

At the rearward position of the carrier 120 this pin moves to a position above the toe 295 of a lifting lever 296 which is rigidly fastened to a horizontal shaft 297.

The shaft 297 is the dipping shaft, and carries at its outer end a crank 298 connected by link 299 to a rocking member 125 134, which is pivoted at 300 and carries a cam roll 133.

The dipping cam 132 upon the main shaft has a projecting portion 301 which engages 120 130

the roller 133 to move this roller downward and cause the toe 295 of the lifting lever to lift the rear end 293 of the rocking lever which causes the suction plunger 288 to move downward to pick up the next sheet or card at 272.

The suction cups take hold of the sheet or card by suction, through suction connections 302.

10 When the toe 301 of the dipping cam moves away from engagement with the roller 133 on the rocking lever 134 the suction cup moves up.

15 The dwell is by this time over and the carrier moves forward carrying the sheet or card along.

20 At the forward end of its travel an air trip member 303 (Figure 14) pivotally mounted at 304 upon the suction cup carrier engages a bolt 305 upon an extended arm 306 of the upper housing 279.

25 This breaks the suction and the sheet or card falls to place for exact positioning by the aligning members.

25 *Detector mechanism.*

30 This is shown diagrammatically in Figures 35 and 36 applied to one form of tripping mechanism that is now used on some presses.

35 The function of the detector mechanism is to prevent an impression of the press whenever there is no card to receive it. If the impression is made without a sheet or card between the die and counter die the counter die becomes smeared with ink and six or more of the succeeding sheets will be smeared up and spoiled so that it is highly essential that there shall be no impression 40 whenever there is no sheet or card present to receive it.

45 Referring to Figures 35 and 36, and describing first the tripping mechanism without reference to my detector mechanism used with it:—

The press plunger 55 sliding in a vertical guideway 313 in a fixed portion 314 of the press is carried on opposite sides of the press by the compression links 54.

50 The compression links are mounted at their lower ends upon eccentrics 53 upon opposite ends of the main driving shaft 52 of the press and these links move the plunger or head 55 of the press up and down in its 55 vertical guideway 313.

A knuckle-toggle connection is provided between the head 55 of the press and counter-block 315 which carries the makeready.

55 The counter-block 315 slides in vertical guides 316 in a fixed part of the press.

A knuckle-link 317 has pin and knuckle bearing and connection with the counter-block 315 at its lower end and with a toggle head member 318 at its upper end.

60 The toggle head 318 has a sliding guide-

way support at 319 from the head of the press, the position of the toggle head along the guideway being subject to control by the rocker arm 320 pivoted at 321 to a fixed part of the press and having slot and pin connection at 322 with the toggle head 318 and an operating arm 323.

Unless the rocking arm 323 is moved into position at which it holds the toggle head off to one side as seen in Figure 36, the knuckle-toggle connection between the head of the press and the counter-block will hang vertically as in Figure 35. When the toggle connection hangs vertically the counter-block 315 is at its lowest position with respect to the head of the press and during an impression this toggle-knuckle mechanism is always vertical as seen in Figure 35.

The rocker arm 323 is normally controlled by a cam 324 upon the main driving shaft 35 of the press cooperating with cam roller 325 pivotally carried upon a lever 326 that is linked to the rocker arm 323 by a connecting rod 327.

25 The lever 326 is pivoted at 328 to the frame work of the press and the mechanism is such that the rocker arm is held in the position to keep the knuckle-toggle mechanism askew unless the roller 325 enters a depression 329 of the cam.

30 In normal operation just before an impression is made the depression 329 of the cam comes under the roller 325 and the cam lever 326 is free to turn and permits the rocker arm to move down which straightens out the toggle.

35 There can be no impression unless the toggle is straightened out as the counter-block will be raised above the die when the head of the press is at its low position, and stop mechanism is provided whereby an operator can prevent downward motion of the rocker arm irrespective of whether or not the cam roller is in position to enter the depression 329 of the cam.

40 In the figures this mechanism is shown as comprising a lever 330 pivoted upon the pivot 321 of the rocker arm and having a face 331 adapted in one position to engage a lug 332 upon the rocker arm.

45 If the operator moves this lever down from the position of the figures that is, from the upper notch 333 to the lower notch 334 the rocker arm will be stopped from moving to straighten out the toggle.

50 The motion of the head 55 of the press will not be interrupted with or affected in any way by change in position of the knuckle-toggle mechanism, moving up and down exactly the same whether the toggle is straightened out or askew, but the counter-block will not engage the die to make an impression if the toggle is maintained askew, and an operator can prevent any impression by pressing down the lever 330 to prevent

the toggle from straightening out when the depression 329 of the cam reaches the roller 325.

In this mechanism an operator feeding 5 by hand can trip the press by moving down the lever 330 to the lower notch 334 whenever it is desired to have the press avoid making an impression and move it up to the upper notch whenever impressions are 10 to be made.

In applying my detector mechanism to this form of tripping mechanism I show in the figures a stop lever 335 pivoted at 336 to the frame of the press, having a toe 337 15 adapted to engage the lug 332 on the rocker arm and having an arm 338 making pin and slot connection at 339 with a balanced lever 340 that is pivoted at 341 to the side 80 of the slidable frame supporting my feed mechanism.

On the end of the main cam shaft 98 of my automatic feeding mechanism I provide a cam 342 and use this cam to operate a rocking lever 343 pivoted at 344 to the 25 slidable frame member 80 in such a way that an extended portion 345 on this rocking lever will engage the balanced lever 340 at 346 to so control the stopping of the rocker arm 320 that the toggle will be stopped 30 from straightening unless a sheet or card is present to receive the succeeding impression.

The rocking lever 343 upon the side of the slidable frame is provided with an upwardly 35 directed toe 347. The roller 348 upon the rocker lever is resiliently pressed toward engagement with the cam 342 by means of a spring 349.

The cam 342 is provided with a depression 40 350 so placed that near the end of each rest period of the turntable this depression comes to the roller. As a result the lever under the stress of the spring 349 turns somewhat moving the toe 347 upwardly.

If a sheet or card is present this toe stops 45 against the sheet or card and the roller is prevented from fully entering the depression 350 on the cam.

If however, a sheet or card is absent then 50 the roller 348 moves inward and the toe moves upward to the dotted position shown in Figure 36. As a result the balance lever 340 engaged at 346 by the projection 345 of the rocking lever is turned to latch the toe 337 of the stop lever in position to engage the lug 332 of the bell crank member 320 controlling the toggle head.

At this time the head of the press is near 55 the beginning of its downward stroke. The depression 329 of the cam 324 of the trip mechanism relieves the trip mechanism and the bell crank 320 moves down so as to stop against the toe 337 of the stop lever as seen in Figure 36.

The cam 342 on the main cam shaft now

moves to lift the roller 348 which moves the toe 347 downward and permits motion of the turntable to its next position.

In moving downward the toe 347 leaves the balancing lever and the stop lever in the 70 position shown in Figure 36 which is that to maintain the knuckle-toggle mechanism askew, holding up the counter-block so as to avoid an impression, and maintained in position by the pressure between the toe 337 75 and lug 332.

In both Figures 35 and 36 the head of the press is shown at its lowest position, its position for making an impression, but in Figure 36 the counter-block has not descended 80 because the knuckle-toggle has been kept from straightening out, due to the absence of a sheet or card, while in Figure 35 it is down making an impression.

It will be noted that the turntable has to 85 move to its next position after the stop lever 335 has latched under the lug 332 of the bell crank lever 320 controlling the toggle head, and the toe 347 moves down out of the way in time to permit this motion.

Figure 35 illustrates conditions as they will be if a sheet or card has been present.

The toe 347 of the lever 343 has moved up and stopped against the sheet or card when the depression 350 on the cam 342 reached 95 the roller 348 of the rocking lever. This stopping against the sheet or card has prevented engagement between the rocking lever and the balanced lever to latch under the lug 332 of the mechanism controlling the 100 toggle mechanism.

As the result when the cam 324 on the main driving shaft of the press moved into a position to release the bell crank, the bell 105 crank moved down and the toggle straightened so as to make an impression when the head of the press is at its low position, that is at the position shown in both Figures 35 and 36.

110 General operation.

The machine is especially applicable to feeding paper or card stock to, and delivering it from, a die stamping press; and when the term "sheet" or "card" is used here or in the claims it must be understood as including either. In any position of rest of the turntable, the gripper opposite the feeder pile may be referred to as being at the "first" position, the gripper over the detector finger 115 347 as at the "second" position, the gripper opposite the dies as at the "third" position, and the gripper opposite the delivery means as at the "fourth" position.

As a preliminary to running a job, the 120 following adjustments are generally made: The whole feed mechanism is moved towards or from the press in accordance with the size of the sheet, and the position of the impression on the latter; this being effected 125 130

by turning the screw 75^b in one direction or the other. The end gages 128, 129 and the side gage 130 are set to such a position with respect to the platform 213 as to result in accurate positioning of the sheet with respect to the dies when the sheet has been fed around to the latter. The frame 403 is moved upon the rails 402 until the end combers 163, 164 are in the proper position to 10 perform their function in connection with a sheet of the particular length to be fed. Likewise, one of the stands 405 is adjusted upon the frame 403 so as to bring one of the side combers, 165 or 165^a, into the proper 15 position, depending upon the width of the sheet and the location of the side gage 130. The support fingers 400 are adjusted, in accordance with the width of the sheet, so as to form supports under the edges of the latter (Fig. 1).

When the turntable 79 comes to rest, the gripper 168 in the "first" position will be open, because of the engagement of the cam 108 above its inner end. The jaw 203 of 25 the puller will be closed. The end combers 163, 164 and the side comber, either 165 or 165^a, will be rocked backwardly and downwardly. The lock pin 159, end gages 128, 129 and side gage 130 will be below the level 30 of the turntable.

After the turntable has come to rest, the platform 213 will be raised, thus causing the pin 159 to enter the socket 161 immediately above it, thereby to effect a final positioning 35 of the turntable and a locking of the turntable in such final position. Upon the rise of the platform 213, the end gages 128, 129 and the side gage 130 come up into operative position, the end gages 128, 129 passing 40 through the slots 162 of the turntable. The rise of the platform, by the contact of its lever 219 with the lifting member 211, effects the lifting of the upper member 203 of the frictional puller, thereby opening the 45 puller ready to receive the edge of the sheet which is just about to be fed.

The sheet is now fed forward by the suction cup carrier 124 and dropped in a position in which its front part is supported upon the edge of the turntable and its two side parts are supported upon the fingers 400, the sheet being in a position in which its front edge is adjacent the front gages 128, 129 and one side edge is adjacent the side gage 130. Thereupon the end comber shaft 176 and side comber shaft 182 are rocked so as to swing up the end combers 163, 164 and the side comber, 165 or 165^a. These combers 55 engage the rear and one side edge of the sheet and push the latter resiliently against the end gages 128, 129 and side gage 130 respectively.

When the combing action of the sheet or card against the end or side gages has taken 60 place, the cam 221 upon the gear 118 will

engage the pin 220 on the lever 219 and move the latter away from beneath the lifter 211, causing the upper member 203 of the frictional puller to close upon the registered sheet. Shortly afterward, the pin 222 on the gear 118 engages the inner end of the arm 224, effecting a rocking of this arm and a movement of the frictional puller rearwardly in its slot. If the sheet is already properly in engagement with the end and side gages, the pads 163, 167 of the puller will merely slide on it, maintaining it closely in such engagement. Otherwise, since the puller moves in a diagonal direction, it will first bring the sheet or card into close engagement with the end and side gages and then slide relatively to it. While the puller is thus operating, and the sheet or card is thus closely held against the end and side gages, the gripper actuating cam 108 makes 75 its slight final movement in a clockwise direction, enabling the gripper 168 to close upon the registered sheet.

The sheet having thus been registered, and gripped in such registered position, the platform 213 descends, carrying the pin 159, end gages 128, 129 and side gage 130 down out of the way of the turntable. The table now makes a quarter turn, carrying the newly fed sheet around to the "second" position, 90 again coming to rest for a sheet or card to be fed to the gripper now at the "first" position.

During the period of rest of the turntable after the newly fed sheet has been brought 95 to the "second" position, the depression 350 of the cam 342 will come opposite to the roll 348 of the lever 343 (Figs. 35 and 36), allowing the spring 349 to move such lever into a position in which its finger 347 engages beneath the under side of the sheet. This engagement of the finger 347 with the sheet will prevent the spring 349 from moving the lever 33 farther, and will prevent 100 such lever from actuating the arm 340 and thereby causing the tripping of the press. Thus, a sheet being present, the impression of the press will take place as usual. If, however, for some reason, no sheet had been fed, the lever 343 would move up to a greater 105 extent, into the position shown in dotted lines in Fig. 36. It would then tilt the arm 340, and move the foot 337 of the lever 333 into the path of the lug 332 of the arm 323. The engagement of the lug 332 with the foot 110 337 would prevent the arm 323 from being rocked downward, thereby to straighten the press toggle, when the depression 329 of the cam 324 came opposite the roller 325. Thus 115 the press would be tripped and an impression 120 stopped from taking place on the next cycle.

On the next quarter turn of the turntable, the sheet is brought into the "third" position, and the impression takes place.

On the next quarter turn of the turntable 130

the sheet just impressed is brought to the "fourth" position (Figures 27 and 28), the sheet being held by the gripper 168. The gripper actuating cam at this time makes its main movement in a clockwise direction (resulting from the engagement of the first step 193 of the cam 106 with the roll 190) effecting the opening of the gripper 168 in the manner described above. The gripper thus releases the sheet, leaving it resting with its front part upon the edge of the turntable and its side parts upon the fingers 400. At this time, the delivery arm 235 swings, in the plane of the sheet, from the position shown in Fig. 27 to that shown in Fig. 28. During this movement, the upper and lower jaws of the delivery gripper 239 pass above and below the sheet, and the upper jaw 256 is closed upon the sheet by the action of the trigger 238 upon end 270 of the pin 264. Thereupon the delivery arm 235 swings back in the plane of the sheet, the latter being thereby withdrawn from the fingers 400; and the delivery gripper then turns downward, under, and outward until it reaches the position shown in Fig. 33, in which the sheet is released and dropped upon a tray or the like.

In view of my invention and disclosure variations and modifications to meet individual whim or particular need will doubtless appear to others skilled in the art and I therefore claim all such in so far as they fall within the reasonable spirit and scope of my invention.

Having thus described my invention, what I claim as new and desire to secure by Letters Patent is:—

1. A die stamping and embossing machine having a main gear and feeding mechanism, a pivot connecting the two at one side, a lock between the press and feeding mechanism at the opposite side, a spur gear carried by the feeding mechanism, engaging with the main press gear when in operative position, and feeding connections carried by the feeding mechanism and driven by said spur gear.

2. A printing press having a main gear, in combination with feeding mechanism adjacent thereto comprising a driving shaft, a gear on the driving shaft connecting with the main gear of the press, driven feeding connections upon the feeding mechanism, adjusting devices for moving them toward and from the press, and a flexible connection between the shaft driving mechanism and the driven feeding connections.

3. A press having a main gear in combination with paper feeding devices therefor comprising a driving shaft, a spur gear thereon connecting with the main gear of the press, a main shaft for the feeding devices, flexible gearing between the said shaft and spur gear shaft, containing a worm gear

and worm and feeding connections driven thereby.

4. A press having a main shaft and gear, a gear connected therewith, a horizontally swinging mount therefor, a vertical shaft 70 driven by the gear, a horizontal shaft, gearing connecting the shafts in such ratio that the vertical shaft shall rotate at the same angular speed as the shaft of the press main gear and feeding devices driven by the vertical shaft and timed by it to synchronize with movement of the press.

5. A press having a main gear, a main shaft therefor, a spur gear connecting with the main gear, a horizontal shaft for the 80 spur gear, a vertical shaft, connection between the horizontal shaft and the vertical shaft, said connection being flexible and including gearing of such proportion that the main shaft of the press and the vertical shaft 85 operate at the same angular speed, feeding devices having a plurality of positions, operating mechanism controlling the feeding devices driven by the vertical shaft and timed by it and an adjustment of the vertical shaft transverse to its length.

6. In a feeding mechanism for presses, a main feed shaft, a Geneva stop mechanism driven thereby, a feeding turntable driven by the Geneva stop mechanism and a pin 95 stop for said turntable inserted and withdrawn by gearing operated by the feeder shaft.

7. A press having a die and counterdie, a turntable for feeding cards to the press 100 having laterally extending fingers to support the sheet or card, means for sequentially clamping the inner edges of successive cards to the turntable in registry with different portions thereof and means for bringing the 105 portions successively in registry with the die and counterdie.

8. A press having a die and counter-die, a turntable, automatic feed mechanism adapted to deliver successive cards into a definite 110 position upon the turntable, a pin and socket lock adapted to bring successive portions of the turntable into exact registry with the position and means for bringing the portions successively into exact registry 115 with a die and counterdie.

9. A press having a die and counter-die, a turntable, automatic feed mechanism adapted to deliver successive cards into a definite position upon the turntable, a tapered pin 120 and socket lock adapted to bring successive portions of the turntable into exact registry with the position and means for bringing the portions successively into exact registry with the die and counterdie.

10. A turntable, a set of stops or gages at the side thereof, means for delivering successive cards to the stops or gages during periods of rest of the turntable, means for clamping the successive sheets or cards to 125

the turntable while engaging the stops or gages and means adapting the turntable to deliver them while clamped into position of dwell in registry with the die and counter-die.

11. A turntable, having spaced portions adapted to automatically deliver successive sheets or cards to a press and a single set of stops or gages for definitely positioning the sheets or cards successively with respect to the spaced portions of the turntable.

12. A turntable for sheet or card delivery to a press and sheet or card stops or gages cooperatively associated with said turntable that do not turn with the latter and adapted to align the sheets or cards to positions of registry with successive portions of the turntable.

13. A press having a die and counter-die, a turntable for stock delivery thereto having successive periods of dwell and movable stops or gages for stock alignment that enter the table to position the stock during each period of dwell and that are removed therefrom after the stock has been positioned and before the end of each period of dwell.

14. A press having a die and counter-die, a turntable adapted to feed stock thereto having successive periods of dwell, and having sockets at uniformly spaced circumferential intervals, a socket for each dwell, a pin lock adapted to register successively with the sockets to draw successive portions of the turntable into exact registry with a position to one side of the turntable, stops or gages for paper alignment to registry with the position and common supporting means for the pin lock and stops or gages for use in placing them in operating positions near the beginning of each period of dwell and in moving them out of the way near the end of each period of dwell.

15. A turntable adapted to feed stock to a press, gages separate therefrom and lateral thereof for aligning the stock with successive portions of the turntable and means for resiliently pushing the stock into engagement with the gages.

16. A turntable adapted to feed stock to a press, gages separate therefrom and lateral thereof for aligning the stock with successive portions of the turntable and combining shafts carrying small spiral springs adapted to push the stock into contact with the gages.

17. A turntable adapted to feed stock to a press, gages separate therefrom and lateral thereof for aligning the stock with successive portions of the turntable, means for resiliently pushing the stock into engagement with the gages and an adjustment for the means to accommodate sheets of different sizes.

18. A turntable adapted to feed stock to a press, gages separate therefrom and lat-

eral thereof for aligning the stock with successive portions of the turntable and means operating in two directions for resiliently pushing the stock into engagement with the gages.

19. A press, a turntable adapted to feed stock thereto and having successive periods of dwell, gages to one side of the turntable and separate therefrom for aligning the stock upon successive portions of the turntable, means for frictionally pulling the stock into engagement with the gages and other means for clamping the stock to the turntable while the stock is being frictionally pulled against the gages.

20. A press, a turntable adapted to feed stock thereto and having successive periods of dwell, gages laterally of the turntable for aligning stock upon successive portions of the turntable, a frictional device mounted upon the turntable for each portion thereof and adapted to frictionally pull the stock into engagement with the gages and means for clamping the stock to the turntable during each period of dwell while it is being frictionally pulled into the gages.

21. A press, a turntable adapted to feed stock thereto and having successive periods of dwell, gages to one side of the turntable and separate therefrom, means for delivering stock into definite position against the gages, socket members upon the turntable having the sockets at equi-distant circumferential intervals around the turntable, a pin lock mating successively with the sockets for bringing different successive portions of the turntable into exact registry with the position during each period of dwell, and means for clamping the stock to the turntable while in position against the gages.

22. A press, a turntable for feeding stock thereto and having successive periods of dwell, removable gages to one side of the turntable for aligning the stock to definite position, means for locking the turntable during each period of dwell so as to bring successive different portions thereof into registry with the position and automatic other means operative during each period of dwell for feeding stock to one portion of the turntable, printing stock at another portion and delivering stock that has been printed from a third portion thereof.

23. A turntable having successive periods of dwell, a single set of gages to one side thereof for aligning stock to a definite position adjacent the turntable, means for bringing successive portions of the turntable into successive registry with the position, means operative during each period of dwell for clamping stock to one portion of the turntable means, to print stock at another portion thereof and means to automatically deliver stock from still another portion thereof.

24. A press, a turntable for feeding stock thereto, supporting structure therefor fastened to the press and an adjustment between the turntable and press adapting it to use with variant size of stock.
25. A press, a turntable for feeding stock thereto, a supporting track rigidly fastened to the press, and means for adjusting the turntable along the track in order to adapt it to use with variant sizes of stock.
26. A press, a turntable for feeding stock thereto, a track therefor fastened to the press, a flexible driving connection between the press and the turntable adapted to permit adjustment of the turntable along the track, and an adjustment of the turntable along the track.
27. A press, a turntable for feeding stock thereto, a track therefor along which the turntable is adjustable in position and an apron hinged to the press at one side and fastened to it at the other and supporting the track.
28. A press, a turntable for feeding stock thereto, a track supporting the turntable, a mount for the track having hinged connection with the press upon one side and a removable fastening upon the other, a driving shaft for the turntable having stationary bearing upon the mount, driving connection therebetween and the press, a splined shaft having universal joint connection with the driving shaft, a worm mounted on the splined shaft, a worm wheel, an operating shaft therefor, bearings and operating connections for the operating shaft, a bearing and shroud or housing for the worm pivotally mounted on the operating shaft, and an adjustment between the turntable and its track.
29. A press, a turntable for feeding stock thereto, a support therefor, automatic devices upon the support for simultaneously operating upon stock at different portions of the turntable, a shaft mounted upon the support for operating the turntable and the devices, and means for imparting continuous rotary motion to the shaft.
30. A press, a turntable for feeding stock thereto, a Geneva drive to the table, gages for one side of the turntable for aligning the stock to definite position, frictional pulling devices mounted upon the turntable and operative at successive portions thereof to frictionally pull the stock against the gages, means for clamping the stock to the turntable during the operation of the frictional puller, continuously rotating cams on the shaft of the turntable controlling the operation of the frictional pullers and driving connection between the Geneva drive and the cams.
31. A press, a turntable for feeding stock thereto, having successive periods of dwell, movable gages to one side of the turntable for aligning the stock to definite position, socket members at uniformly spaced circumferential intervals upon the table, a pin lock adapted to register successively in the sockets to draw successive portions of the turntable into exact registry with the position, common supporting means for the pin lock and the stops or gages adapted to place these stops or gages in operating position near the beginning of each period of rest of the turntable, jaws for the frictional pulling devices spring-pressed toward closure, an opening connection between the common support and the jaws whereby the jaws are opened when the support moves to position the lock and stops or gages, and a release for the connection operating by means timed with the turning mechanism.
32. A press, a turntable for feeding stock thereto from a pile and having successive periods of rest, means for operating the turntable intermittently and automatic means for delivering successive sheets or cards from the pile to the turntable during the respective periods of rest.
33. A press, a turntable for feeding stock thereto, having four periods of rest during each revolution providing four portions of surface adapted successively to register with the die and counterdie of the press, automatic means operative during each period of rest for feeding stock to the first portion, for aligning and clamping the stock so fed to the turntable, for applying detector mechanism at the second portion adapted to avoid stamping during the succeeding stroke if the stock has not been properly placed for printing in the third portion and for removing printed stock from the fourth portion.
34. A mechanism for feeding sheets to a press, comprising a turntable, a plurality of sheet retaining members carried thereby, means for imparting partial rotations to said turntable with intervening periods of rest whereby said sheet retaining members arrive at sheet receiving and impression positions, and a detector mechanism operating at one period of rest and controlling the impression operation of the press at a period of rest of the turntable.
35. A mechanism for feeding sheets to a press, comprising a turntable, a plurality of sheet retaining members carried thereby, means for imparting partial rotations to said turntable with intervening periods of rest whereby said sheet retaining members arrive successively at sheet retaining, sheet detecting, and impression positions, and a detector mechanism operating at the sheet detecting position and controlling the impression operation of the press at the next succeeding period of rest of the turntable.
36. A mechanism for feeding sheets to a press, comprising a turntable, a plurality of sheet retaining members carried thereby,

means for imparting partial rotations to said turntable with intervening periods of rest, whereby said sheet retaining members arrive successively at sheet retaining, sheet detecting, impression and sheet delivery positions, and a detector mechanism operating at sheet detecting position and controlling the impression operation of the press at the next succeeding period of rest of the turntable.

37. In a press having automatic feeding mechanism, a turntable for delivering stock to the press, a pile elevator having stock thereon, a suction cup carrier for delivering stock from the pile to the turntable, a plunger on the carrier having vertical range of motion and supporting spaced suction cups, a carriage adapted to move back and forth above and between the pile and the table for transferring successive sheets from the pile to the table, a horizontal slidable support for the carrier upon the carriage rigid therewith and slidable with respect to the carrier, means for resiliently rearwardly pressing the carrier upon its support and a rearward stop for the carrier operative before the carriage attains its rearmost position to give a period of dwell to the carrier while permitting continuous back and forth motion of the carriage, in order to permit pick-up operation of the suction cups.

38. Suction cup carrier mechanism comprising a housing, a horizontal guideway therein, a carriage in the guideway, a rack upon the carriage rigid therewith, a gear meshing with the rack and having bearing support upon the housing, automatic means for operating the gear in order to move the carriage back and forth, a carrier loosely supported between front and rear abutments upon spaced horizontal rods of the carriage, means resiliently pressing the carrier against its rear abutments, a lateral projection upon the carrier and a rearward stop upon the housing to engage the projection and stop the carrier before the carriage reaches its most rearward position to permit a period of rest for the carrier in which to pick-up stock while continuously moving the carriage back and forth.

39. A press, a turntable having successive periods of rest, means for delivering stock to the turntable at one side thereof away from the press, automatic detector mechanism applied to detect the presence or absence of stock at another side of the turntable intermediate of the press and said means, and an automatic control by the detector of the operation of the press such that an absence of stock during operation of the detector prevents the next impression of the press.

40. A press, a turntable having successive periods of rest, a sheet detector mechanism, means applied to the turntable at different

sides thereof during each period of rest respectively delivering stock to the turntable, applying said detector mechanism with respect to said turntable and printing stock, and a control between the operation of said detector mechanism and of the press.

41. A turntable having successive periods of rest in first, second, third and fourth positions, means operative during each period of rest for delivering and clamping stock to that portion of the turntable which is in first position, a detector applied to that portion of the turntable which is in second position, a press operative at the portion in third position and a control between the detector and the operation of the press in the period of rest succeeding that in which said detector operates.

42. A turntable having successive periods of rest, a press at one side thereof adapted to operate during each period of rest and a detector operative in one period of rest to control the operation of the press in the succeeding period of rest.

43. A press having a plunger operating in a vertical guideway, a counter-block axially beneath the plunger and operating in another vertical guideway, a toggle-head having a horizontal guideway support upon the bottom of the plunger, a toggle-knuckle connection between the head and the block, a lever pivoted on the press and by its position controlling the horizontal position of the toggle-head in order to control the distance between the counter-block and plunger, and adapted to hold the toggle-knuckle connection askew in order to hold the block raised with respect to the plunger, cam means operative by and synchronized with the press for maintaining the lever in a position to hold the knuckle-toggle askew to render printing inoperative, a release on the cam adapted to permit the lever to move to straighten out the toggle before the plunger reaches its low or printing position, a turntable to one side of the press and having successive periods of rest synchronized to take place with the printing operations, means operative during each period of rest to deliver stock at one portion of the turntable to apply a detector to stock at another portion thereof and to print stock at a third portion, and an automatic control between the operation of the detector and the operation of the lever.

44. A press having a plunger operating in a vertical guideway, a counter-block axially beneath the plunger and operating in another vertical guideway, a toggle-head having horizontal guideway support upon the bottom of the plunger, a toggle-knuckle connection between the head and the block, a lever pivoted on the press and by its position controlling the horizontal position of the toggle-head in order to control the dis-

tance between the counter-block and plunger, and adapted to hold the toggle-knuckle connection askew in order to hold the block raised with respect to the plunger, cam 5 means operative by and synchronized with the press for maintaining the lever in a position to hold the knuckle-toggle askew to render printing inoperative, a release on the cam adapted to permit the lever to move 10 to straighten out the toggle before the plunger reaches its low or printing position, a stop-lever pivoted to the press and adapted to lock the lever from turning, preventing straightening of the knuckle-toggle, 15 a balancing lever controlling the position of the stop-lever, a turntable adapted to feed stock to the press and having successive pe-

riods of rest, a rocking lever having a stationary pivot, a roller at one end and a detector toe at the other and adapted to stop 20 against stock upon the turntable, a cam engaging the roller and normally maintaining it in position away from the stock, a spring maintaining engagement between the roller and cam, a depression in one portion of the 25 cam permitting the rocking lever to move its toe upwardly to engage stock, upon the turntable, cooperating parts between the rocking lever and the balanced lever adapted to engage when the toe moves upwardly 30 when it does not meet and stop against stock upon the turntable in such a way as to lock the lever controlling the knuckle toggle.

CYRUS HAWKINS.
